(57) **CLAIM**

The ornamental design for a footguard, as shown and described.

DESCRIPTION

FIG. 1 is a top-front-right perspective view of a footguard, showing my design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.

The broken lines in the drawings depict unclaimed environmental subject matter.

1 Claim, 5 Drawing Sheets
